UNITED STATES PATENT OFFICE

ARTHUR W. HULSON, OF KEOKUK, IOWA

DUMPING SECTION FOR GRATES

Application filed November 2, 1931. Serial No. 572,651.

The invention relates to grates for boiler and other furnaces and is designed primarily for locomotive grates. Such grates commonly embody a dumping section at the front 5 of the grate which may be downwardly swung, allowing the fireman to rake the firebox contents through the opening thus formed, when the fire is to be dumped. These dumping sections have been heretofore of 10 one-piece construction and have thus been subject to severe warping and to breakage under the influence of expansion and moreover have necessitated substitution of a complete new section even if only a portion of 15 the old section has become burnt out or otherwise damaged. Such complete substitution has been objectionable not only on account of the expense involved, but the difficulty of making the substitution, due largely to the 20 weight of the dumping sections.

My invention aims to provide a new and improved dumping section of sectional form in which ample provision is made for expansion and contraction without injury, and 25 this sectional construction also allows easy replacement of any injured part or parts and permits further use of any other part or parts still in condition for further service.

With the foregoing in view, the invention 30 resides in the novel subject matter hereinafter described and claimed, description being accomplished by reference to the accompanying drawing.

Fig. 1 is a top plan view of a dumping 35 section constructed in accordance with the invention.

Fig. 2 is a rear edge view.

Fig. 3 is an end elevation.

Fig. 4 is a vertical sectional view on line 40 4—4 of Fig. 1.

Fig. 5 is a disassembled perspective view partly broken away and in section, showing a portion of the frame which demountably carries the fire-supporting means.

The preferred construction has been illustrated and will be specifically described, with the understanding however that within the scope of the invention as claimed, variations 50 may be made.

A marginal frame F is provided having a

removable section S, and the fire-supporting means M is carried by and interlocked with said marginal frame, so that no portion of said fire-supporting means can be removed from the frame until the frame section S is 55 detached. Upon such detachment however, any or all portions of the fire-supporting means, may be removed and another portion or portions readily substituted.

The frame F is preferably of the specific 60 construction disclosed, being formed only of two pieces and the necessary bolts for connecting them. One piece of this frame embodies a horizontal bar 6 adapted to extend transversely at the front end of a fire-box, 65 said bar preferably having ash-discharge and air-admission openings 7. Rigidly connected with the ends of the bar 6 and preferably formed integrally therewith, are two lateral arms 8 which extend toward the rear end 70 of the fire-box, said arms being preferably provided with ash-discharge and air-admission slots 9. The rear lower corners of the arms 8 are notched as at 10 for a purpose 75 to appear, and the front ends of these arms are provided with integral lugs 11 which are also integral with the bar 6, one of said lugs being provided with a continuous-walled bearing socket 12 while the other is provided 80 with a bearing socket 12' which opens not only through the outer side of the lug, but through the lower end of the latter. Both of the bearing sockets 12 and 12' are adapted 85 for engagement with the conventional bearing trunnions (not shown) to pivotally support the entire dump section.

Also integral with the bar 6 and disposed between the arms 8, is an intermediate arm 13 (or a plurality of them). The rear end 90 of the arm 13 is provided with a downwardly projecting lug 14 for engagement with the conventional dumping means so that the entire grate section may be swung downwardly when the fire is to be dumped, and later restored to its horizontal position. The arms 8 and 13 are all detachably secured by bolts 15 to the detachable frame section S, said section being in the form of a bar opposed to the bar 6. The ends of this bar are notched 95 as at 16 to interfit with the notched ends of 100

the arms 8, and the central portion of said bar is formed with another notch 17 which receives the front extremity of the arm 13.

The inner longitudinal edge of the bar 6 5 is formed with a groove 18, and a similar groove 19 is formed in the inner longitudinal edge of the bar or removable frame section S. The upper edge of arm 13 is preferably flush with the lower side of the groove 18.

10 The two grooves 18 and 19 receive projecting ribs 20 and 21 on the fire-supporting means M, thereby securely locking said means to the frame F, as long as the bar or detachable frame section S is bolted in place. Upon

15 removal of the bolts 15 and detachment of the member S however, the fire-supporting means M may be quickly and easily removed, allowing it to be either repaired or replaced.

The means M preferably consists of a plurality of rectangular plates 22 having ash-discharge and air-admission slots 23. Obviously, any damaged plate or plates can be removed and a new plate or plates substituted, allowing further use of any of the 25 plates which may be in such condition as to permit further service thereof. Then too, should the frame F be severely damaged and the fire-supporting means M still intact, a new frame may be substituted at small cost,

30 and due to the sectional construction of the device, it may be more readily taken out of the fire-box and the replacement device may be more easily installed. Moreover, due to said sectional construction, expansion and 35 contraction may take place freely and with no danger of warping and breakage.

While excellent results are obtainable from the details disclosed, attention is again invited to the fact that within the scope of 40 the invention as claimed, variations may be made.

I claim:—

1. In a dumping section for a grate, a frame 45 comprising a horizontal bar for disposition transversely across one end of a firebox, two horizontal arms rigidly connected with the ends of said bar and projecting laterally therefrom, said arms having free ends, a second horizontal bar opposite the first named 50 bar, said bars having longitudinal grooves between the upper and lower edges of their inner opposed sides, and means detachably securing said second horizontal bar to said 55 free ends of said arms; fire-supporting plates within the confines of and abutting said frame, the ends of said plates being provided with integral ribs received in said 60 grooves and allowing removal of said plates only when said second bar is detached, bearing 65 means on the frame for engagement with extraneous means to pivotally support said frame, and means on said frame for engagement with extraneous dumping means for the grate section.

65 2. In a dumping section for a grate, a

frame comprising a horizontal bar for disposition transversely across one end of a firebox, one side of said bar having a longitudinal groove between its upper and lower edges, two horizontal arms rigidly joined to the ends of said bar and projecting laterally from said one side thereof, the upper sides of said arms being above said grooves, an intermediate arm between the aforesaid arms and rigidly joined to said bar, the upper side of said intermediate arm being flush with the lower side of said groove, all of said arms having free ends, a second horizontal bar opposite the first named bar and having a longitudinal groove between the upper and lower edges of its inner side, and means detachably securing said second bar to said free ends of all of said arms; fire-supporting plates within the confines of said frame, said plates abutting said bars and said two arms, all of said plates having ribs on their ends removably received in said grooves but removable therefrom only when said second bar is detached, at least one of said plates lying upon said intermediate arm, bearing means on the frame for engagement with extraneous means to pivotally support said frame, and means on said frame for engagement with extraneous dumping means for the grate section.

In testimony whereof I affix my signature.

ARTHUR W. HULSON.
